Atty.

UNITED STATES PATENT OFFICE.

BERITA BARNETT, OF LONDON, ENGLAND.

SMOKE-BELL.

SPECIFICATION forming part of Letters Patent No. 710,834, dated October 7, 1902.

Application filed November 11, 1901. Serial No. 81,871. (No model.)

To all whom it may concern:

Be it known that I, BERITA BARNETT, married woman, a subject of the King of Great Britain and Ireland, residing at Craighton 5 House, 17 Elgin Crescent, London, W., England, have invented certain new and useful Improvements in Smoke-Bells, (for which I have made application for Letters Patent in Great Britain, No. 18,352, and dated the 13th 10 day of September, 1901,) of which the following is a specification.

This invention relates to improvements in smut-catchers for gas-brackets and other gas-fittings; and its object is to construct a smut- 15 catcher which can be readily applied to gas-brackets whereon globes or chimneys of different heights are employed and in which the smut-catching plate or screen can be readily removed for cleaning purposes.

20 The invention consists of a base-plate which is passed over the gas-burner and from which upwardly-projecting arms extend capable of being bent into any desired position, which arms carry at their upper end a ring or the 25 like, upon which the removable plate or smut-catcher itself rests, the arms being formed so as to admit of the upper parts thereof being readily broken off when so desired to adapt the device for use upon gas-brackets employing 30 globes or chimneys of varying heights.

The invention is illustrated in the accompanying drawings, in which—

Figure 1 is an elevation of the smut-catcher as applied to a gas-bracket, the ordinary 35 globe being shown in section. Fig. 2 is a plan of the same, while Figs. 3 and 4 are detail views of the upper ends of the supporting-arms. Fig. 5 is a sectional detail.

In carrying the invention into effect a 40 metal or other base-plate is provided having a central hole therein, which is screw-threaded to fit over the ordinary gas-burner *e* under the ordinary globe-holder *f* of the gas-bracket, and this plate is provided with two, three, or 45 more short arms of uniform length, which project outwardly from the base-plate. At the end of these short arms two, three, or more branches *b* of equal length project upwardly, such arms being provided at their 50 upper ends with a number of projecting

knobs, or the arms themselves may be bent to form projecting ridges at equal distances apart.

A metal or other ring *d*, perforated with small holes, rests upon the outermost of the 55 projecting knobs or ridges of the upwardly-extending arms *b*, and upon this ring or upper support the smut-catcher *c* itself is carried, this smut-catcher being provided in the form of a metal or other disk of either convex 60 or flat formation, and such disk may be suitably plated, enameled, or otherwise treated when so desired. The object of the ring *d* is to keep the branches *b* firmly in position when the plate *c* is removed for cleaning purposes. 65

The smut-catcher *c* has a number of holes therein corresponding with the holes in the ring *d*, which supports the same, such holes being sufficiently large to admit of the upper ends of the projecting branches *b* to pass 70 easily therethrough. The ordinary globe *a* is carried by the globe-holder *f*, which is also of the usual form, and the projecting arms *b* of the smut-catcher pass upwardly through the globe and extend out at the top thereof 75 to a distance of about an inch from the upper edge of the same.

As shown in Fig. 3, the arms *b* are provided with projecting ridges *g*, such ridges *g* being arranged on each of the arms, preferably at 80 equal distances from each other, so that parts of such arms may be broken away, thus allowing the ring *d* to be always maintained at a suitable distance from the upper edge of the globe *a*, so as not to impede the draft. 85 By this means the smut-catcher is always maintained at any desired height above the globe. The pieces of these arms are broken away, preferably immediately beneath any one of the series of the projecting ridges there- 90 on, so as to leave a projecting part on each branch of equal length which will pass through the holes in the ring and in the disk or plate which forms the smut-catcher *c*.

A modified form of the supporting-arms is 95 shown in Fig. 4, in which projecting knobs *h* are employed instead of the ridges, as shown in Fig. 3. The upwardly-projecting arms *b* are made as narrow as possible, so as to throw but little shadow onto the globe.

When fitting the smut-catching device to a gas-bracket, the projecting arms *b* are bent outward after the base-plate has been fitted onto the gas-burner into such a position that they will not interfere with the screwing on of the globe-holder, and after this globe-holder has been secured the arms are bent up into an upright position, so that none of them will come into contact with the flame when the gas is lighted. It will be seen that by the use of a smut-catcher, as hereinbefore described, the globe or chimney is not liable to be cracked by the heated metal, no part of the frame or the disk itself touching the globe. When the holder is fixed to the burner, the frame itself does not require to be removed for cleaning purposes, as the disk at the top of the holder can be readily removed by lifting the same when so required. The arms *b* may either project straight upward from the end of the short arms of the base-plate, or they may be slightly curved, as shown in the drawings.

The invention may be modified in several details without departing from the essential features thereof, as hereinbefore set forth, and the different parts of the smut-catcher and

its support may be constructed of metal or any other suitable material.

Having now described my invention, what I claim as new, and desire to secure by Letters Patent, is—

1. A smut-catching device for gas-burners consisting of a base-plate fitting over the burner, arms projecting upwardly from said base-plate, a ring carried at the upper ends of said arms and a smut-catching plate resting on said ring, substantially as hereinbefore described.

2. A smut-catching device for gas-burners consisting of a base-plate fitting over the burner, arms projecting upwardly from said base-plate, each of said arms having a number of projections near the top thereof to adapt the device for different heights of globes, a ring carried on said projections and a smut-catching plate supported by said ring substantially as hereinbefore described.

In witness whereof I have hereunto set my hand in presence of two witnesses.

BERITA BARNETT.

Witnesses:

ALBERT E. PARKER,
A. I. BARNETT.
